UNITED STATES PATENT OFFICE.

WILLIAM P. CARSTARPHEN, OF DENVER, COLORADO, ASSIGNOR, BY DIRECT AND MESNE ASSIGNMENTS, TO NITE-EYE LIGHT CORPORATION, OF DENVER, COLORADO, A CORPORATION OF COLORADO.

HEADLIGHT REFLECTOR.

Application filed October 9, 1923. Serial No. 667,497.

To all whom it may concern:

Be it known that I, WILLIAM P. CARSTARPHEN, a citizen of the United States, residing at the city and county of Denver 5 and State of Colorado, have invented certain new and useful Improvements in Headlight Reflectors; and I do declare the following to be a full, clear, and exact description of the invention, such as will enable others skilled in the art to which it 10 appertains to make and use the same, reference being had to the accompanying drawings, and to the characters of reference marked thereon, which form a part of this specification.

This invention relates to improvements in reflectors and has reference more particularly to improvements in reflectors used in connection with automobile headlights.

It is well known to everyone who drives an automobile that the present headlights are defective in this, that they cause rays to be projected in such a direction that they strike the eyes of approaching drivers and blind them, causing thereby great discomfort and sometimes serious accidents.

It is the object of this invention to produce a reflector that shall be so designed that it will cause the light to be projected in the desired direction and which will make it possible to get a proper distribution of light without any danger of the production of rays that will blind an approaching driver.

This invention will be described in connection with automobile headlights, as this is the principal use to which it is to be put. I want it understood, however, that it is my intention to employ the reflector in many other relations, as, for example, in the illumination of show windows, signs, etc.

It is well known to persons familiar with the laws of optics that a paraboloidal reflector has the property of converging all rays, which enter it in a direction parallel to its axis, to a point. This point is the focal point of the reflector. Conversely, if there is a source of light located at the focal point, the light rays that strike the surface of the reflector are reflected in a direction parallel to the axis of the reflector. Of course the latter case is strictly true only if the source of light is a point which, however, can never be obtained, as even the

most condensed filament has a considerable dimension. It is evident that if the source of light is a point, or of very small dimension, and located at the focal point, there will be no dispersion of the reflected rays, which will be projected as a condensed cylinder of light. From such a source of light no blinding rays will emerge in a direction that will cause a blinding glare to eyes located outside of the cylindrical beam.

Although a source of light, such as described, would be thoroughly safe, as far as the question of objectionable glare is concerned, it is evident that it is not practical, as the light would illuminate only a small portion of the surface of the road. In order to obtain a proper distribution of light on the road, the filament has been located either to the front of or to the rear of the focal point. When the filament is located to the front of the focal point the reflected light will emerge in the form of a cone whose vertex is located in front of the source of light and when the source of light is to the rear of the focal point, the rays will emerge as a cone whose vertex is to the rear of the source of light. By either of the above arrangements, a good distribution of light may be obtained on the road. As soon as the light is moved away from the focal point of a paraboloidal reflector it projects rays that are highly objectionable.

It is evident that if the rays from a headlight are prevented from spreading to any considerable extent in a vertical plane, they may be permitted to spread to any extent in a horizontal plane without causing objectionable glare.

It is the object of this invention to produce a reflector that shall be so constructed that it will prevent any rays of light to be projected upwardly and at the same time give a satisfactory downward distribution and a sidewise distribution of the light.

This invention, in its broadest aspect, consists of making the reflecting surfaces unsymmetrical so that with the light at a certain point, the rays will be projected at unequal angles on the several sides of the axis of the reflector. The surfaces employed by me are as nearly parabolical as they can be made under the circumstances, but each

reflector has several reflecting sections, each of which has a different axis from the others. In this manner a reflector having the desirable properties of a paraboloidal reflector as to parallel rays is obtained and which also distributes the lights differently in different directions.

In order to better and more clearly describe my invention, I shall have reference to the accompanying drawings in which my invention is illustrated, and in which:

Fig. 1 shows a front elevation of my improved reflector;

Fig. 2 is a section taken on line 2-2, Fig. 1;

Fig. 3 is a section taken on line 3-3, Fig. 1.

Fig. 4 is a section, of a slightly modified form, taken on line 4-4, Fig. 1;

Fig. 5 is a section, of a modified form, taken on line 5-5, Fig. 1;

Fig. 6 is a side elevation of a headlight provided with a reflector made in accordance with the modification shown in Fig. 4 and shows the direction of the rays of light as they emerge from the reflector;

Fig. 7 is a top plan view showing the direction of the rays as they emerge from reflectors constructed in accordance with Fig. 5; and

Fig. 8 is a view similar to that of Fig. 7, but showing the direction of the rays from a reflector constructed in accordance with Fig. 3.

The same reference characters will be employed to designate the same parts throughout the different views.

Numeral 1 designates the reflector portion as a whole, whose specific construction will be hereinafter described. The reflector has an outwardly extending circular flange 2 which is secured to a ring 3 by means of clamping screws 4 which can be loosened so as to permit the reflector to be rotated relative to the ring and which may be tightened so as to clamp the reflector and ring against relative rotation. Ring 3 is provided with bayonet slots 5 and an annular bead 6. The object of the ring 3 is to permit my reflector to be used in connection with lamps of different sizes, as, by this means different sizes of rings can be made and the proper sized ring selected for the lamp to be fitted to. The purpose of the adjustment is to permit the reflector to be rotated about the axis of the lamp to the extent required to produce the best distribution of the light.

It will be noticed from Fig. 1 and from the several sections that my reflector is not circular in appearance, but is oblong and approaches an elliptical shape.

In order to more clearly illustrate my invention, I have taken vertical and horizontal sections. In Fig. 2 there is shown

a vertical axial section which is a true parabola whose focal point is indicated by F. When the lamp is so located that the filament is at the focal point, the rays will emerge in parallel lines in the manner shown.

The horizontal section corresponding to section 2-2 is shown in Fig. 3. In this section the curved portions 7-8, 9-10, are both parabolic, but each has a different axis which passes through the same focal point F, but are divergent.

The axis of one half of the reflecting surface is indicated by F, G and the axis of the other half by F, H. These axes diverge to the extent of making an angle of about 32 degrees with each other.

Of course the angle may be greater or less than this, but from experiments that have been made, a divergence of 32 degrees appears to give the best results.

It will be readily apparent that if a reflector is constructed which has a vertical section like that shown in Fig. 2 and a horizontal section like that shown in Fig. 3, with the intermediate portions substantially parabolic, or as nearly so as the construction will permit, the light will be

projected in a thin fan-shaped beam. The spread in a horizontal direction can be made as small or as great as may be necessary to suit the particular case.

It is often desirable to have the light project at different angles on different sides of the axis of the reflector. In Fig. 4 I have shown a reflector in which the upper portion, from

7 to 8, is a parabolic curve with a focus at F and an axis F, A., while the lower portion 9 to 10 is also parabolic, but its axis is along the line F, B. and its focal point at F.

With a reflector having a vertical section like that shown in Fig. 4, the rays reflected from the upper part will be projected in a substantially parallel, horizontal beam, while the rays from the lower portion will be deflected downwardly towards the ground.

In Fig. 6 I have shown a side elevation of a lamp and the general direction of the rays that emerge from the lamp.

When it is desired, the horizontal section of the reflector can be made like that shown in Fig. 5, in which the portion

7-8 has its axis on line F, G. and the portion 9-10 its axis on line F, H.

The side 7-8 is placed on the outside and directs rays of light to the outside of the road while the rays from the part 9-10 are thrown on the road and illuminate the same.

A plan view of a pair of automobile headlights is shown in Fig. 7.

It is of course understood that, since the source of light is never a point, there will be some dispersion other than that shown.

The sections of the reflector between the horizontal and the vertical are not as a rule true parabolas, and that therefore the

light reflected from them will modify, to

some extent, the illumination described. It is, however, apparent from the above that by making the reflectors unsymmetrical and employing wherever possible parabolic curves, it is possible to get a wide distribution of the light and still retain the source of light at the focal point. As explained above, a parabolic reflector will cause no glare due to the reflected light. if the filament is located at the focal point, but this has been impractical due to the fact that paraboloidal reflectors have been employed and these would only cast a beam of light of a diameter equal to that of the reflector if the light source were at the focus.

Having now described my invention, what I claim as new is:

An illuminating device for automobiles comprising, in combination, two lamps

adapted to be applied in spaced relation to the forward end of an automobile, said lamps each comprising an integral reflector divided vertically into two substantially parabolic surfaces placed side by side, each of which has an axis which crosses the axis of the other surface at the focal point, the axes of the adjacent reflector surfaces of each lamp being substantially parallel, while the axes of the outside reflector surfaces are outwardly inclined to the right and left respectively, whereby the roadway lying in front of the lamps will receive light from the reflector surfaces having the parallel axes and the light reflected from the outer reflector surfaces will illuminate the sides of the roadway.

In testimony whereof I affix my signature.

WILLIAM P. CARSTARPHEN.
